UNITED STATES PATENT OFFICE.

WILLIAM A. E. HENRICI, OF CHELSEA, MASSACHUSETTS.

DESIGN FOR A LAUNDRY-IRON.

SPECIFICATION forming part of Design No. 25,519, dated May 19, 1896.

Application filed April 20, 1896. Serial No. 588,384. Term of patent 14 years.

To all whom it may concern:

Be it known that I, WILLIAM A. E. HENRICI, of Chelsea, county of Suffolk, and State of Massachusetts, have invented and produced a certain new and useful Design for

5 Laundry-Irons, of which the following is a specification, reference being had to the accompanying drawing, forming a part thereof.

In the drawing forming part of this specification a laundry-iron showing my design is illustrated in perspective.

10 The leading feature of my design for a laundry-iron consists in a cylindrical body and a flattened foot convexo-convex in shape extended beneath the body.

15 The cylindrical body *a* shown as enlarged

at its top at *a'* and hollow or concaved at *a''*, rises from a thin flattened foot *b*, extended beneath the body, and convexo-convex in contour, the body being eccentric to the center 20 of the foot.

What I claim is—

The design for a laundry-iron, substantially as herein shown and described.

In testimony whereof I have signed my 25 name to this specification in the presence of two subscribing witnesses.

WILLIAM A. E. HENRICI.

Witnesses:

JOHN C. EDWARDS,
AUGUSTA E. DEAN.
